PUNCHING MACHINE

Jessie T. Ivy, Seattle, Wash.

Application March 13, 1945, Serial No. 582,516

9 Claims. (Cl. 164—119)

This invention relates to improvements in punching tools and machines, and has reference more particularly to hand portable punching machines but is not necessarily confined thereto; the present machine being adapted primarily for the punching of small holes in sheet metal and being especially useful in the airplane manufacturing and like industries for the punching of holes for rivets, bolts, etc., in the sheet metal members used in the making of the wings, fuselage and other parts of the airplane.

It is the principal object of this invention to provide a hand portable machine of the above stated kind, including a die and reciprocating punch for forming the holes, and having a plate clamp and stripper member and novel means for effecting and for coordinating the functional movements of the stripper and punch so that, after the tool has been applied, the stripper will be moved to engage the piece to be punched as a clamp prior to and during the action of the punch thereon, and the punch, after punching its hole, will be withdrawn from the piece prior to the release of the stripper therefrom, and finally, the stripper will be lifted into the clear for the release of the punched piece and to permit the withdrawal of the tool, or its application at another place on the plate.

It is also an object of this invention to effect the functional movements of the punch and stripper member through the mediacy of a novel arrangement of links and levers in a toggle clamp assembly of parts, driven by a crankshaft for a most effective application of power, particularly in the driving of the punch through a piece of sheet metal.

Still another object of the invention is to provide a machine using the crankshaft as the medium through which the punch and stripper are actuated and which shaft may be rotated in either direction to accomplish the same coordination of movements of the punch and stripper.

Still further objects of the invention are to be found in the details of construction and in the combination of parts, and in their mode of operation as will hereinafter be fully described.

In accomplishing the above stated and other objects of the invention, I have provided the improved details of construction, the preferred forms of which are illustrated in the accompanying drawings, wherein—

Fig. 1 is a front edge view of the present machine.

Fig. 2 is a side view of the same; parts of the

frame portion being broken away for purpose of better illustration and understanding.

Fig. 3 is a cross section taken on line 3—3 in Fig. 2, showing the crankshaft and its connection with the toggle linkage which actuates the punch and stripper.

Fig. 4 is a cross section on line 4—4 in Fig. 2.

Figs. 5, 6 and 7 respectively are views with some parts in cross section, showing the connection of the toggle linkage with the crankshaft, and illustrating the action of the linkage for effecting the coordinated movements of the punch and stripper.

Fig. 8 is a sectional detail showing the guiding and mounting bearings or blocks for the punch and stripper.

Referring more in detail to the drawings—

In its present preferred form of construction, the tool, or machine, comprises a substantial metal frame or housing in which the movable parts, including punch stripper, crankshaft and linkage, are contained. The frame comprises what may be termed its handle, or holding portion 1; the die mounting bracket 2 that extends from the lower end of the handle at a right angle thereto, and the housing 3 that extends from the upper end portion of the handle and is spaced somewhat above the bracket, leaving a clearance space 4 between them, as noted in Fig. 2. Mounted in the outer end portion of the bracket 2 is a die 5, here shown to be of tubular form, vertically disposed and removably seated in a pocket 6 in the bracket 2. The bracket is formed with an opening 7 coinciding with the passage through the die for the discharge of punched out pieces.

The housing 3, as shown best in Fig. 3, comprises spaced opposite side walls 8 and 8' between which a crankshaft 9 extends. The throw of the crankshaft is contained within the housing and the opposite end portions of the shaft are revolvably contained in bearings 10 in the side walls. At one end, the crankshaft is equipped with a driving worm gear 11 with which a driven worm 12 is in operative mesh, as shown in Fig. 1.

It will be understood by reference to Fig. 2 that the worm 12 is mounted on a driving shaft 13, which shaft is revolvably in bearings 14—14 in a gear case 15. The case is adjustably applied to the side wall of housing 3 to overlie the gear 11 and the peripheral wall of the case is notched, as at 16, to receive similarly shaped projections on the housing wall, thus to keep the case from rotating. The case is held in place by the head

17' of a bolt 17 that extends through a hole 18 in the case and is threaded into the crankshaft. A friction washer 19 is located between the case and bolt head, as noted in Fig. 3.

It is a feature of the invention that, by loosening the bolt, the case may be rotatably adjusted to place the drive shaft in the most advantageous position. The outer end of the drive shaft 13 is equipped with means at its end to receive any desirable form of flexible shaft driving connection, or it may have the chuck of an electric drill or similar machine applied thereto as the power medium.

The throw of the crank shaft mounts a pitman, or link 21 which, in Fig. 2, is shown to extend in a horizontal direction and at its outer end to be pivotally mounted on the central portion of a transverse pivot bolt or pin 22. Mounted on the pin, closely adjacent the opposite sides of the pitman, are the lower ends of a pair of upwardly extended links 23-23' which, at their upper ends, are pivotally connected by a pivot bolt 26 with a lug or web 28 in the upper outer end portion of the housing 3.

Extending downwardly from the housing 3, directly above the die mounting portion of the bracket 2, is a tubular guide member 30, which at its lower end, terminates at an interval above the die 5. Fixed within the lower end of the tubular guide portion 30 is a bearing sleeve or bushing 35, and reciprocally slidable through this sleeve, is the clamp and stripper tube 36 which, at its upper end, is adjustably threaded into a guide and bearing block 38. The block 38 is reciprocally contained in that portion of the tubular guide member 30 that is immediately above the sleeve 35. The sleeve is removable from the guide member, but is held against accidental displacement in use by a set screw 39 threaded into the member 30 and seated against the sleeve, as noted in Fig. 2.

The stripper member 36 threads at its upper end into the block 38 and is held against unthreading by a set screw 40 that threads through the block as shown in Fig. 4. The screw passes through a vertical slot 41 in the guideway 30 and does not interfere with the reciprocal action of the part 38.

Reciprocally contained coaxially within the stripper tube is a punch 42. This punch comprises a straight shaft that extends at its upper end beyond the stripper tube and through a bearing block 44 in which it is fixed by nuts 45 and 45' threaded thereonto and tightened against upper and lower sides of the block. The block 44 is reciprocally contained in the upper end portion of the tubular guideway 30. A pair of levers 48 and 48' have upper ends pivotally connected with the outer ends of the pivot pin 22, and intermediate their ends, are pivotally mounted on transversely aligned pivot studs 49-49' that extend from the opposite sides of the block 44 and through vertical slots 50 in the side walls of the guideway.

The lower end portions of the levers 48-48' are somewhat flared and are formed with horizontally directed cam slots 52 which contain therein studs 53 which extend from the opposite sides of the block 38 and through vertical slots 54 in the guideway.

The connection of the pitman 21 with the links 23-23 and levers 48-48' is such that with a 180° turn of the crank shaft, the links and levers are moved from the position of vertical alignment in which they are shown in Figs. 1

and 7, to the angular position or relationship shown in Fig. 5. This action of the toggle linkage causes the guide blocks 38 and 44 both to be lifted; the block 44 being moved upwardly in the guideway by reason of the toggle action of the connected links and the other by reason of the toggle action as modified by that movement that is caused by reason of the design of cam slots 52 in which studs 53 are contained.

In order that the movements of the stripper and punch be coordinated for the purposes previously mentioned, the cam slots 52 are definitely designed, and this will be best understood by reference to Figs. 5, 6 and 7. In these views, a sheet metal plate that is to be punched is designated by reference character *p*, and a template for gauging the spacing or location of holes to be punched therein is designated at *t*, and the center about which the crank shaft rotates is designated at *C*. The toggle linkage will be fully extended when the crank shaft is in the position shown in Fig. 5, and will be fully retracted when the shaft has turned through an arc of 180° from the position of Fig. 5.

When the parts are in the position seen in Fig. 7, the punch and stripper are then retracted to such a position that their lower ends are flush with the flat lower surface of the guide bearing 30 and sleeve 35. The tool may then be applied to the metal sheet. When the template is used, the punch is applied by locating the upper end of the die 5 in a hole of the template. Assuming that the tool has been applied as in Fig. 7 and that the crank shaft, starting from the position shown in Fig. 7, has rotated through the angle indicated by arrow *a* in Fig. 6, the punch and stripper will have been simultaneously extended and brought into contact with the plate; the stripper then engaging the plate with a clamping effect that holds it firmly against the die for the subsequent hole forming action of the punch.

It will here be explained that prior to a punching operation, the extent to which the stripper 42 will be extended for this clamping effect should be accurately determined. This is done by placing on the die a piece of metal of the same thickness of that to be punched. Then the crank shaft is rotated to bring the linkage to the position shown in Fig. 6, and the stripper 36 is then unthreaded from the block 38 to adjust its end surface firmly against the plate. Then set screw 40 is tightened to hold this adjustment. In this position of the toggle linkage, the studs 53, on block 38, are located in the cam slots 52 at the positions where downward travel of the block, by reason of the movement of the toggle linkage and cam action ceases. The design of both cam slots is alike. Each is of angular formation and is directed transversely across the base end portion of its lever 48 or 48' and each comprises an end portion 52a at one side of a medial location that is arcuately curved about a center that is coincident with the axial center of the pivot 49 and it comprises an opposite end portion 52b that is substantially straight but is inclined somewhat toward the axial center about which the portion 52a is formed so that, with the toggle linkage moving from the position in which it is shown in Fig. 6, toward the position of Fig. 5, there will be no further downward movement of the block 38 either through the straightening out of the links or through the cam action, but the block will be held stationary.

Assuming that the parts have been actuated

from positions of Fig. 7, and have reached the position of Fig. 6 at which the lower end of the stripper member 36 is clamped tightly against the plate *p*, farther extending of the toggle linkage to the position of Fig. 5, causes the punch that is affixed to block 44, to be projected through the plate *p* to form the hole therein. While at the same time, the stripper 36 is retained clamped against the plate.

After the hole has been punched, the continued 10 rotation of the crank shaft from position in Fig. 5, retracts the toggle, and this moves block 44 upwardly, to withdraw the punch clear of the plate; then, as the punch leaves the plate, the stripper and punch move upwardly together, and 15 finally are restored to the starting position which corresponds to the position of parts in Fig. 7.

In the operation of the device, the punch pressure is effected directly by the toggle linkage acting against the block 44 while the action of the 20 stripper is through the toggle linkage as modified by the cam slot and stud connection between the levers 48 and the block 38.

If it is desired to set the machine for work 25 on plate of a different thickness, proper adjustment must be made in the setting of the stripper and in some cases, readjustment of the punch is required. Adjustment of the punch is effected by making adjustment of the holding nuts 30 45-45' which are applied thereon and which engage the upper and lower faces of the block 44.

It is also anticipated that punches of different 35 diameters might be interchangeably used and this would require the removal of a stripper and punch from position and replacing with parts of the desired size.

Devices of this character are especially useful where a hand portable tool is required. The tool may be conveniently held by grasping the handle 40 portion 1 and any suitable form of driving device may be applied to the worm shaft 13. It is anticipated that the usual form of electric drill might be used as the power medium merely by applying the chuck of the drill to the end of the shaft 13.

Tools of this character may be made of various materials, of various sizes, and it is possible that modifications in structure might be made without departing from the spirit of the invention.

Having thus described my invention, what I claim as new therein and desire to secure by Letters Patent is:

1. A punch of the character described comprising a frame including a punch die, a punch and a stripper reciprocally movable on the frame toward and from the die, a rotatably driven shaft, and a toggle linkage connected with the frame and with the punch and with the stripper, and means connecting the toggle linkage with the rotatably driven shaft to effect an advancing and a withdrawal movement of the punch, and a synchronized reciprocal action of the stripper to move it into contact with the piece to be punched and to maintain it there during the advancing and withdrawal travel of the punch, and then to retract the stripper.

2. A punch as recited in claim 1 wherein the frame portion includes a guide bearing, the stripper is reciprocally movable in the guide bearing and is of tubular form and the punch is reciprocally mounted in the tubular stripper.

3. A punch of the character described comprising a frame including a punch die and a guide bearing alined therewith, a stripper sleeve re-

ciprocally mounted in the bearing, a punch reciprocally contained in the stripper sleeve to contact with the die for punching a piece placed between them, a rotatably driven crank shaft, a toggle linkage pivotally connected at one end to the frame and having connection with the punch and stripper, and operable by rotation of the crank shaft to effect an advancing and withdrawal movement of the punch and a synchronized action of the stripper to cause it to be moved into clamping contact with the punched piece during the advancing and withdrawal of the punch and then to be retracted to release the piece.

4. A punch as recited in claim 3 wherein the toggle linkage comprises a pair of pivotally joined links, one being connected at its outer end to the frame and the other link being pivotally connected with the punch and having a pin and cam slot connection with the stripper, and the intermediate joint of the linkage being connected with the crank shaft whereby, in its rotation, it effects the reciprocal action of punch and stripper.

5. A punch as recited in claim 3 wherein the toggle linkage comprises a pair of pivotally joined links; one being connected at its outer end to the frame and the other link being pivotally connected with the punch and having a pin and cam slot connection with the stripper, and the intermediate joint of the linkage being connected with the crank shaft whereby, in its rotation, it effects the reciprocal action of the punch and stripper; the pin and cam slot connection providing the synchronized actions of the punch and stripper.

6. A portable punch of the character described comprising a frame including a punch die for support of a piece to be punched, and a guide bearing alined with the die, a tubular stripper sleeve mounted on the bearing for endwise movement from and toward the die, a punch reciprocally mounted in the stripper sleeve, a pair of pivotally joined links forming a toggle; the link at one end thereof being pivotally fixed to the frame, and the link at the other end thereof having pivotal connection with the punch for effecting its reciprocal action and an operative connection with the stripper sleeve, a crank shaft mounted on the frame, a connection between the crank shaft and toggle for actuating it to cause reciprocal actions of the punch and stripper; said stripper having a stud fixed thereto and the second mentioned link of the toggle having a cam slot containing the stud therein, and so shaped as to effect an endwise movement of the stripper into holding contact with a work piece during the extension and retraction of the punch, and then to retract it from the held piece.

7. A punch as recited in claim 6 wherein the inner end of the stripper sleeve and the inner end of the punch are mounted on bearing blocks reciprocally contained in the guide bearing, and the second mentioned link of the toggle has a fixed pivotal connection with the bearing block of the punch and wherein the stud which operates in the cam slot is mounted on the bearing block of the stripper sleeve.

8. A portable punch of the character described comprising a frame including a support for a work piece to be punched, and a guide bearing alined therewith, a tubular stripper sleeve mounted reciprocally in the bearing, a punch reciprocally mounted in the sleeve, guide blocks fixed to the inner ends of the punch and sleeve,

studs extended from the opposite sides thereof, two pairs of toggle links, with upper ends pivotally fixed in the frame and lower links pivotally mounted on the studs of the punch guide block, and a crank shaft having a rod connection with the toggles whereby with each rotation of the shaft, the toggles will be moved from a retracted position to an extended position and then back to a retracted position to effect the actuation of the punch through a work piece and its retraction therefrom; said lower links of the toggles

having cam slots therein containing the studs of the stripper sleeve guide block and said slots being so shaped as to cause the sleeve to be actuated into holding contact with the piece during the extension and retraction of the punch therefrom and then to be moved to retracted position.

5 9. A punch as in claim 8 wherein the punch and the sleeve are adjustable endwise in their 10 respective guide blocks.

JESSIE T. IVY.
